COMBINED CONTAINER AND CARRIER FOR BEVERAGE CANS OR THE LIKE

Alfred A. Schroeder, P.O. Box 12039, San Antonio, Tex.
Continuation of design application Ser. No. 71,350, Aug.
20, 1962. This application Apr. 28, 1964, Ser. No.
79,714

Term of patent 14 years

(Cl. D58—26)

Fig. 3

Fig. 2

FIG. 1 is a top perspective view of a combined container and carrier for beverage cans or the like embodying my design;

FIG. 2 is a top perspective view thereof on an enlarged scale with the cover in open position; and

FIG. 3 is an elevational view thereof on an enlarged scale with the cover in open position.

This application is a continuation of my earlier application, Serial No. D-71,350, filed August 20, 1962, and now abandoned.

I claim:

The ornamental design for a combined container and carrier for beverage cans or the like, substantially as shown and described.
